UNITED STATES PATENT OFFICE.

RALPH R. LARSEN, OF QUINCY, MASSACHUSETTS.

DESIGN FOR A TOY.

Application filed March 18, 1922. Serial No. 1,237. Term of patent 14 years.

To all whom it may concern:

Be it known that I, RALPH R. LARSEN, a citizen of the United States, residing at Quincy, in the county of Norfolk and State of Massachusetts, have invented a new, original, and ornamental Design for a Toy, of which the following is a specification, reference being had to the accompanying drawings, forming a part thereof.

In the drawings, Fig. 1 is a perspective view.

Fig. 2 is a top view.

I claim—

The ornamental design for a toy as shown.

RALPH R. LARSEN.
